UNITED STATES PATENT OFFICE.

ALBERT BALL, OF CLAREMONT, NEW HAMPSHIRE, ASSIGNOR, BY MESNE ASSIGNMENTS, TO SULLIVAN MACHINERY COMPANY, OF BOSTON, MASSACHUSETTS, A CORPORATION OF MASSACHUSETTS.

CHANNELING-MACHINE.

1,206,288.

Specification of Letters Patent. Patented Nov. 28, 1916.

Application filed December 27, 1907. Serial No. 408,254.

To all whom it may concern:

Be it known that I, ALBERT BALL, a citizen of the United States, and a resident of Claremont, in the county of Sullivan and 5 State of New Hampshire, have invented an Improvement in Channeling-Machines, of which the following description, in connection with the accompanying drawings, is a specification, like letters on the drawings 10 representing like parts.

My invention relates to stone working machines, being intended more particularly for quarrying machines of the channeler type, although in some of its features it may 15 have application to devices other than channeling machines.

My invention will be best understood by reference to the following description when taken in connection with the accompanying 20 illustration showing one specific embodiment thereof, while its scope will be more particularly pointed out in the appended claims.

In the drawings: Figure 1 is a front elevation of a channeling machine embodying 25 one form of my invention; Fig. 2 is an elevation, on an enlarged scale, partially in section, showing the lower end of the tool guide upon the machine in Fig. 1; Fig. 3 is a section in plan on the line 3—3 in Fig. 2; Fig. 30 4 is a detail showing in end elevation a portion of the tool and socket member shown in Fig. 2; Fig. 5 is an end elevation, partially in section, showing the principal working parts of the channeler illustrated 35 in Fig. 1; Fig. 6 is a section in plan, on an enlarged scale, taken through the tool-supporting standard on the line 6—6 in Fig. 1; Fig. 7 is a vertical sectional elevation taken 40 through the cylinder and controlling valve of one of the two pressure fluid piston hammer tools shown as employed upon the channeler in Fig. 1; Fig. 8 is a sectional elevation showing the hoisting device upon the frame of the channeler in Fig. 1; and Fig. 45 9 is a detail showing a tool-lifting attachment.

Referring to the drawings and to the embodiment of the invention there shown for 50 illustrative purposes, the same is disclosed as applied to a usual form of track chan-

neler having the main frame or truck 1 supported upon the wheels 2, the latter adapted to track with the rails 3 customarily laid upon the bottom of the quarry.

Any desired or suitable construction of 55 machine may be employed and any desired means may be used for advancing the same along the line of cut, but in the illustrated form of my invention the channeler is shown as provided with the truck-driving engine 60 4 of the pressure-fluid type, mounted upon the frame and connected through a well-known form of reversing mechanism to drive the machine along the trackway in either direction through the worm shaft 5, worm 65 gears 6 and axles 7.

At the working side of the machine suitable means are provided for supporting the channeling tools and the actuating devices therefor. Such supporting means may be 70 of any suitable construction according to the character of the work or the type of machine to which the invention is applied, but in the disclosed embodiment thereof there is provided a trunnion shaft 8 to which there is 75 adjustably bolted a trunnion block 9, upon the hub portion 10 of which is mounted the standard 11 so that it may be adjusted to any desired angular inclination in the plane of the channel groove. The standard is held 80 rigidly in its selected position of adjustment upon the trunnion block by the clamping plate 12 and the clamping bolts 13. The trunnion block may be unclamped from and again clamped to the shaft in a fresh position so that the standard may be tipped back from a vertical position for angle cutting, or may be adjusted to either end of the machine, as is usual in this class of apparatus. 85

The tool-actuating devices are carried 90 upon the sliding frame 14, which is mounted to slide vertically upon the standard, the latter being provided with retaining gibs 15. The sliding frame with its tool-actuating devices is elevated or depressed to retract or 95 advance the said devices relatively to the work by means of suitable feed mechanism, the same herein comprising the feed screw 16 rotatably held against longitudinal movement in the arched portion 17 of the stand- 100

ard 11, the lower end of the screw having threaded engagement with the threaded member 18 secured to the upper portion of the sliding frame. The upper protruding 5 end of the screw is provided with a usual ratchet and pawl device 19 connected to the hand-lever 20, whereby the feed screw may be turned by the operator and the required advancement or retraction of the sliding frame obtained.

In machines of this class it is usual to provide one or more channeling tools directly connected to a reciprocating tool-actuating device, so that the tools themselves are reciprocated up and down in the cut. In the present instance, however, I have shown the tool non-reciprocatively associated with the actuating device, so that, while arranged to receive the impact of the actuating device, 15 it is not connected to reciprocate therewith. While my invention is applicable to single tool-actuating units, I have herein disclosed the same as embodied in a channeler having two channeling units mounted side by side, 20 each upon the sliding frame 14, each unit having tool-striking means embodied in a pressure-fluid tool engine of the piston hammer or impact type. Operatively related to each of said tool engines is a tool or set of 25 tools maintained in such relation thereto as to receive the impact each of its piston hammer.

Referring more particularly to Fig. 1 the two piston-hammer tools 21 are secured to 30 the sliding frame 14, being each located so that its hammer piston 22 will strike its tool or gang of tools 23 directly beneath where the tools are loosely held with their cutting edges resting against the rock and 35 their opposite ends to receive the impact of the hammer members.

Means are preferably provided to guide the tools and particularly near their cutting ends, so that, as they are carried with the 40 channeler with their cutting ends resting in the line of cut and receiving the rapid recurring blows of the hammers, they may be held accurately in the intended line of cut, and means are also preferably employed so that 45 as the tool is moved along the rock with its edge against the same it may be carried along against any consequent resistance by some positive support or rest engaging the tool. The upper ends of the tools 23 preferably pass through suitable guides upon the 50 sliding frame just below where they are struck by the hammers 22. These guides are shown as comprising suitably formed shoulders or recesses (see Fig. 6) in the sliding frame, to which are bolted the retaining straps 24, the tools being adapted to slide endwise between the straps and the frame. The lower ends of the tools are shown as 55 guided by devices carried upon an upright

guide-plate 25, the latter bolted to the face 60 of the sliding frame, but having a depending guide-supporting portion which extends below the frame and down into the channel groove in association with the cutting tools, with which latter it is carried along in the 70 cut as the machine advances.

By referring to Figs. 2 and 3 it will be seen that the inner vertical edge of the tool 75 23 rests against the outer vertical edge of the guide plate so that the latter acts as a rigid abutment for the leading one of the two tools in case the latter encounters resistance as it is dragged or pushed along on the bottom of the cut by the advance of the machine. The tool is prevented from vibrating or moving laterally out of the line of cut by means of the pair of supporting and guiding ears 26 secured to the lower end of the guide plate and closely overlying the flat 80 faces of the tool (see Figs. 2 and 3).

While the greater resistance to advance 85 movement lengthwise the cut is encountered by the leading tool of the pair, which resistance, however, is opposed by the rigid guiding plate, as described, the following or trailing tool should preferably be provided with some means to hold it up in position against the tool guide and prevent it from dragging behind. For this purpose it is preferably engaged by some kind of a socket holder, 90 the latter being such as to permit the ready removal of the tool for the purpose of changing tools and substituting one of greater length as the cut deepens. In the drawings I have shown a socket holder 27 100 for each tool arranged just above the guiding ears 26, which holder keeps the trailing one of the two tools up against the guide plate. To make this socket holder readily removable, the same is in the form of a U-shaped strap having inturned ends 28 adapted to slide in vertical grooves formed in a projection of the guide plate 25. The socket piece 27 is provided with a handle portion 29 which, overlying the face of the tool, extends upward through the guiding straps 24 and terminates just below the top of the tool. At any time, therefore, the socket piece may be lifted up out of its grooved seat in the guide plate by the handle 29 for the 105 purpose of changing the tools, as hereafter described.

The guide plate being secured to the sliding frame descends with the latter, as the 110 cut deepens and the channeling units are fed toward the work, thereby keeping the guiding and supporting devices described in close association with the cutting ends of the tools at or near the bottom of the channel groove.

In cutting the channel groove as the cut 115 deepens, it will finally become necessary to substitute tools of greater length to obtain

a deeper cut. When this stage is reached the guide plate 25 can then be disconnected from the sliding frame 14 and the latter, together with the cylinders 21, elevated by the 5 feed adjusting screw 16, the tool guide with the tools remaining in the bottom of the cut. When the frame has been raised by an amount equal to the increased length of the new tools to be substituted, the guide plate 10 is then again rigidly secured to the frame and a fresh set of tools substituted. The tools may be readily removed by taking off the clamping straps 24 thereby releasing the tops of the tools, and then drawing up the 15 socket holders 27 by their handles 29, this leaving the lower end of each tool free to be swung out from the guiding ears 26 and lifted out from the cut. The new tools can then be slipped between the supporting ears 20 26, new socket holders inserted having longer handles, corresponding to the increased length of the new tools, and finally the guiding straps 24 placed in position. This type of channeler requires less labor 25 and time to change tools, despite the fact that they are engaged by guiding devices in the cut, than does the ordinary type of channeling machine.

Any suitable fastening between the guiding plate and the sliding frame may be employed. Preferably such fastening should provide for the adjustment of the plate upon the frame, as described. In the illustrated form of my invention the guide plate 30 is shown as extending above the height needed for the shorter tools and provided with an extra set of bolt holes 30 at such distance from the next adjacent lower set of holes that when the frame is raised as described 35 and the guiding plate secured thereto in its newly adjusted position corresponding to the increased length of tools the upper set of bolts will pass through the extra set of holes 30. If another change of tools 40 is required for a third depth of cut, the machine at the outset may be equipped with a still longer guide plate than the one herein shown, thereby permitting the same to be used for all tool lengths, or the plate itself 45 may be changed with the tools.

In order to keep the cut clean and particularly at and in advance of the cutting edges of the tools so that their sliding advance along the bottom of the channel groove during the cutting operation may not be impeded, there is preferably provided means for positively clearing the cut, and, for such purposes, I have herein shown a water conduit 31 formed in the face of the guide plate 50 itself, and leading downwardly to the bottom of the tool guide whence it separates into two divergent branches 32, acting to direct the water along the bottom of the cut beneath the cutting edges. The conduit 31 is

formed by a groove in the face of the guide 65 plate closed by the overlying plate 33. The latter is provided at its upper edge with a connection 34 to which may be applied a hose 35 adapted to be connected with any suitable source of water under pressure. 70

While I have here shown the tools 23 as single, the same may each consist of several tools arranged in the form of a gang, and, in referring herein to the tool provided for a channeling unit, it is to be understood that I 75 refer to the tools collectively, either single or multiple, provided for that unit.

As a convenient means for raising either the guiding plate or the tools, and particularly the former, out of the cut, I have 80 shown a hoisting device arranged near the top of the standard and adapted to be operated by the runner to assist in lifting the tool guides or tools out of the cut. This device consists of the winch 36 (Fig. 8) secured to the shaft 37, the opposite end of which carries the gear 38 meshing with the pinion 39. When it is desired to lift the tool guide, after the same has been uncoupled from the frame, one end of a suitable chain 85 may be fastened to the guide and the opposite end to the winch 36 which can then be turned by a handle 40 secured to turn the pinion 39. On the arch piece 17 of the standard is pivoted a pawl 41 (Fig. 1) 95 adapted to engage with the teeth of the gear 38 and prevent backward movement of the same.

The standard 11 has connection with the usual adjustable brace rod 42, the latter extending diagonally back and having its other end removably connected to the opposite or rear edge of the frame, so that it may be adjustably moved with the standard when the latter is shifted to the opposite end of the machine, or may be lengthened or shortened to tip the standard forward or backward. 100 105

The two actuating units may be of any desired construction, but are preferably, as 110 stated, of the piston-hammer type. Any suitable construction of piston-hammer tool may be employed for this purpose, and in Fig. 7 I have shown a hammer tool well adapted for this purpose, although of a well-known and usual construction. In the hammer-tool shown the piston 22 is reciprocated through the medium of pressure fluid admitted under the control of the valve 46 from the admission port 43 alternately to 115 opposite ends of the cylinder through the ports 44 and 45. The valve is shown as admitting pressure fluid through the port 44 and exhausting the same from the lower end of the cylinder through the lower exhaust 120 port 47. Pressure fluid is admitted to opposite ends of the valve through the axial passages 48 and 49, the latter connected to the 125

admission port 43 by the restricted inlets 50 and 51, respectively. As the piston moves down the grooved portion thereof 52 finally places in communication the two ports 53 and 54,—the former connected to the lower end of the controlling valve and the latter to the lower exhaust port 47, whereby the pressure at the bottom of the valve drops and the valve thereupon reverses connecting 10 the port 45 with the pressure space 43, and the port 44 with the upper exhaust port 55. On the return movement of the piston the valve is again reversed by connecting the upper valve port 56 with the port 57, the latter connected to the upper exhaust port 55. Pressure fluid is admitted both to the hammer tools 23 and the truck-driving engine from any suitable source and through any suitable connections (not shown).

20 By providing a cutting tool non-reciprocatively associated with the tool-actuating device, but adapted to receive the impact of such device, the reciprocating parts are made so light that a very high speed of operation can be obtained. This is particularly true where a pressure-fluid impact-hammer of the type described is employed, which hammer can be practically run at a speed of from one thousand to twelve hundred strokes per minute. Greater rapidity in the cutting action and more efficient operation is not only obtained from this high speed, but also from the mode of cutting, wherein the tool is advanced along the bottom of the cut while held against the work and receiving the impact of the rapidly reciprocated piston-hammer.

In the ordinary type of channeler the gang of tools being reciprocated with the 40 actuating device tend to be whipped or vibrated from side to side, which not only causes considerable and sometimes excessive wear upon the sides of the tools but also tends to make a crooked cut. These difficulties are avoided in the present channeler where the tools rest upon the rock and are not reciprocated with the actuating device, thereby producing a more accurate channel groove and securing a longer life to the 50 tools. The duplex form of machine is an advantage in this type not only from the increased cutting capacity, but since it permits a guide or support to be located between the tools adjacent the cutting edges and 55 thereby provides that the leading tool will be rigidly braced for cutting advance in either direction, while keeping the leading end of the tool free from attachments which might serve as obstructions in preventing 60 the tool from being carried close up to the end of the cut. By the use of the piston-hammer tool described the duplex form of machine, moreover, is scarcely of greater bulk as to its actuating parts than the ordinary channeler.

Under some conditions of operation, as, for example, where the bottom of the cut is too soft to allow the tool to be dragged along the bottom by its entire weight, or for other reasons, it may be desirable to counterbalance wholly or in part the weight of the 70 drill so that the cutting edge of the tool may be lifted free from the bottom of the cut, or a sufficient lift may be exerted upon the tool, to permit it to be dragged along without 75 difficulty.

Various means may be employed for this purpose, and, for illustrative purposes only, I have shown in Fig. 9 an attachment which may be applied to the described form of 80 channeling machine. Referring to Fig. 9 the upper or exposed shank of each tool is provided with a clamp or other attachment 58 to which is secured the spring 59, the latter connected to the lever arm 60, which 85 may be raised or lowered by the hand lever 61 pivoted at 64 upon the guide plate 25 or a part attached thereto to stretch the spring. Both tools as shown are provided with an attachment of this description. With the 90 hand levers upright, and as shown in full lines, the springs are designed to exert no lift, or substantially no lift, upon the tool. When the hand levers are thrown over, for example, to the dotted line position shown, 95 the spring will be stretched and the tool more or less lifted. Pins 62 are provided to hold the levers in their normal position, and, when depressed, as shown in dotted line, 100 they may be held in position by any suitable fastening devices, such as the removable pins 63. Preferably the position of the levers 61 when thrown to stretch the springs will be selected so that the stretched spring in each case will just about balance the 105 weight of the tool and raise the same from the bottom of the cut. It is obvious, however, that the springs may be strengthened or weakened, or the levers may be moved to a final position such that the weight of the 110 tool in either case may be only partially counterbalanced.

While I have shown and described one form of my invention, it is to be understood that the same is not limited to the details of construction or to the specific application herein made thereof, or to the particular means whereby the principles of the invention are disclosed or carried out, but that 115 extensive modifications may be made in the disclosed embodiment of the invention without departing from the spirit thereof.

I claim:

1. The method of cutting a channel groove which consists in advancing the cutting tool in substantially the same plane along the rock with the cutting edge resting loosely thereagainst, and at the same time delivering to the opposite end thereof a series of rapidly recurring hammer blows. 130

2. The method of cutting a channel groove which consists in advancing the cutting tool in substantially the same plane along the rock with the cutting edge resting loosely thereagainst, and at the same time delivering to the opposite end thereof a series of rapidly recurring hammer blows and delivering fluid to said cutting edge.
3. The method of cutting a channel groove which consists in advancing the cutting tool in substantially the same plane along the rock with the cutting edge resting loosely thereagainst at such a rate that successive applications of the cutting edges are caused to overlap and at the same time delivering to the opposite end thereof a series of rapidly recurring hammer blows.
4. A channeling machine having a piston hammer tool-actuating device, a cutting tool adapted to receive the impact of the hammer, a traveling support on which the hammer and the tool may be moved along the rock to cut a channel groove and means to hold the cutting edge loosely in contact with the rock during such travel.
5. A channeling machine having a pressure-fluid operated piston hammer, a cutting tool adapted to receive the impact of said hammer, means for advancing the hammer and the tool along the line of cut and means to hold the tool loosely against the rock at the bottom of the cut during such advance.
6. A channeling machine having a main support, a piston hammer tool actuating device, means supporting said device slidably mounted upon said support, a cutting tool adapted to receive the impact of said device, means to cause the travel of said support to cause the tool to cut a channel groove and means for holding the tool in contact with the bottom of the channel groove during such travel.
7. A channeling machine having a truck, a standard mounted at the side thereof, a sliding frame upon said standard, a fluid-pressure piston-hammer tool mounted upon said frame, means for feeding said frame upon said standard and means on said frame for loosely holding a cutting tool normally disposed in the channel to receive the impact of said hammer tool while the said truck is moved along a rectilinear path.
8. A channeling machine having a truck, a standard mounted at the side thereof, a sliding frame upon said standard, a fluid pressure piston-hammer tool mounted upon said frame, means for feeding said frame upon said standard, rigid means on said frame normally disposed within the channel and extending toward the bottom thereof, a cutting tool normally disposed in the channel adjacent said last mentioned means, and means for loosely holding said tool in position to receive the impact of said hammer
- tool while the said truck is moved along a rectilinear path.
9. A channeling machine having a truck, a standard mounted at the side thereof, a sliding frame upon said standard, a fluid pressure piston-hammer tool mounted upon said frame, means for feeding said frame upon said standard, rigid means on said frame normally disposed within the channel and extending toward the bottom thereof, a cutting tool normally disposed in the channel adjacent said last mentioned means, means for loosely holding said tool in position to receive the impact of said hammer tool while the said truck is moved along a rectilinear path, and means for delivering fluid to the cutting edge of said tool.
10. A channeling machine having a plurality of separate cutting tools, a piston hammer actuating device for each cutting tool, means for progressively advancing the said devices and said cutting tools along the rock to cut a channel groove and means for holding said tools in the same cutting plane with their edges resting loosely against the rock.
11. A channeling machine having a truck, a standard, a support adjustably mounted upon said standard, a plurality of pressure-fluid, piston-hammer tools arranged side by side upon said support, and a plurality of separate cutting tools operatively arranged with relation to said hammer-tools to receive the impact thereof and means to hold the tools against the work.
12. A channeling machine having a reciprocatory hammer member, a tool to receive the impact thereof, guiding means for the cutting end of said tool and means for adjusting said guiding means to enter and advance with the cut as the cut deepens.
13. A channeling machine having a reciprocatory hammer member, a tool adapted to receive the impact thereof, means for progressively advancing said hammer member and tool to cut a channel groove, and means within the channel groove to provide lateral support for the lower end of said tool to assist the advance thereof.
14. A channeling machine having reciprocatory hammer actuating means, a pair of tools adapted to receive the impact of said hammer means, means for progressively advancing said tools to cut a channel groove and a common tool-supporting means between the cutting ends thereof.
15. A channeling machine having a plurality of reciprocating hammer members, a tool for each hammer member arranged to receive the impact thereof, means for advancing said hammer members and tools to cut a channel groove, and a rigid support for the tools extending between said tools into the channel groove.
16. A channeling machine having a plu-

rality of reciprocatory hammer members, a plurality of impact receiving tools, one for each hammer member, and tool guiding means entering the channel groove for engagement with said tools.

17. A channeling machine having a pair of tools adapted to be held loosely against the rock, means for striking said tools, and means adapted to enter the channel groove adjacent the cutting ends of the tools for pressing the leading tool forward in the direction of travel.

18. A channeling machine having a truck, a standard, a sliding frame thereon, a percussive tool, and means secured to the frame and adapted to extend into the channel groove to support the tool thereat.

19. A channeling machine having a tool-striking means, a cutting tool to receive the impact thereof, means for supporting the tool within the channel groove, and means for advancing said striking means and tool-supporting means toward the work as the cut deepens.

20. A channeling machine having a tool-actuating device, a percussive cutting tool, means for progressively advancing the same along the rock to cut a channel groove, and means for feeding water to the edges and sides of the cutting tool.

21. A channeling machine having a tool-actuating device, a percussive cutting tool, means for engaging the tool within the channel groove and means for conducting water through said tool-engaging means to the cutting edges and sides of said tool.

22. A channeling machine having a reciprocatory hammer member, a tool adapted to rest against the rock and receive the impact of said hammer member, means permitting the advance of said tool and hammer member to cut a channel groove, and means for clearing the cut in advance of the cutting edge of said tool to permit the unimpeded advancement thereof.

23. A channeling machine having a tool, a socket holding device for engaging the tool within the channel groove and means accessible to the operator for releasing the tool from said socket device to permit withdrawal.

24. A channeling machine having a percussive tool-actuating device, a tool, means connected to the machine and extending into the channel for guiding the tool within the channel groove, while permitting up and down movement of the tool under the impact of said percussive device, and means for hoisting the said guiding means upon the channeling machine.

25. A channeling machine having a reciprocatory hammer, a tool to receive the impact thereof, a tool guiding member connected to the machine and extending into the cut to hold the tool loosely to permit

up and down movement thereof under the action of said hammer, and means upon the machine for hoisting the guiding member out of the cut.

26. A channeling machine having a reciprocating hammer member, means to hold the tool loosely in the channel groove during travel of the machine to permit the up and down movement of the tool under the impact of the hammer member, a tool adapted to receive the impact thereof, means for progressively advancing said hammer member and tool to cut a channel groove, and means tending to lift the tool during the travel of the machine.

27. A channeling machine having a reciprocatory hammer member, a tool to receive the impact thereof, guiding means for loosely guiding the cutting end of said tool within the channel groove, while permitting vertical movement of the tool under impact of the hammer member, and means having provision for adjusting said guiding means for entering and advancing in the cut as the cut deepens.

28. A channeling machine having a plurality of tools adapted to receive each the impact of a hammer member, means for advancing said tools to cut a channel groove while holding said tools in the channel groove and having provision for means adapted to prevent the following or trailing tool from dragging behind during such advance.

29. A channeling machine having a reciprocatory hammer member, a cutting tool, a traveling support for advancing said hammer member and tool to cut a channel groove, said tool being maintained with its cutting edge in substantially constant contact with the work, and means on said support and within the channel groove for guiding the said tool.

30. A channeling machine having a traveling support, a hammer member, a cutting tool adapted to receive said hammer member, connections between the tool and said support and extending into the cut to guide and maintain the tool therein during the travel of the machine, and means for adjusting said guiding means and said hammer member on said support toward or from the work.

31. A channeling machine having a traveling support, a hammer member therein, a tool held on said support within the channel groove during the cutting thereof, and adapted to receive the impact of said hammer member, and guiding means for said tool connected with said support, and extending into the channel groove.

32. A channeling machine having a traveling support, a pair of cutting tools, a holder, means for supporting said holder between the tools, to project into the channel

groove and holding the tools loosely therein during the travel of the machine, and piston hammer means for delivering hammer blows to said cutting tools.

5 33. A channeling machine having a traveling support, a pair of cutting tools, a standard, a sliding frame on said standard, a holder located on said standard to project into the channel groove between the
10 tools to hold and guide the same therein,

and a pair of pressure fluid piston hammer devices to actuate said cutting tools.

In testimony whereof, I have signed my name to this specification, in the presence of two subscribing witnesses.
